UNITED STATES PATENT OFFICE.

JAMES L. BERNARD, OF BEAVER, PENNSYLVANIA.

SAFETY SCREEN.

1,422,409.

Specification of Letters Patent. Patented July 11, 1922.

Application filed May 31, 1921. Serial No. 473,991.

To all whom it may concern:

Be it known that I, JAMES L. BERNARD, a citizen of the United States, and resident of Beaver, in the county of Beaver and State of Pennsylvania, have invented certain new and useful Improvements in Safety Screens, of which the following is a specification.

This invention relates to a safety screen 10 adapted to prevent flying objects from striking an operator of a machine or other device.

One object of my invention is to provide a light mesh screen that will have sufficiently 15 fine mesh to prevent objects passing therethrough and yet will be sufficiently open to permit substantially unobstructed vision therethrough.

Another object is to provide a screen of 20 the class described that will be sufficiently flexible to fold or drape itself around the hands or arms of the operator when he reaches under the screen to manipulate his work.

25 In the accompanying drawings, Figure 1 is an end elevation showing my invention applied to a laboratory table having suitable testing apparatus thereon.

Figure 2 is a front side elevation thereof. 30 Figure 3 is an enlarged section of the screen mesh showing its structure.

Figure 4 is an enlarged end view of the mesh.

Figure 5 is a side elevation of a power 35 punch showing my screen applied thereto.

Figure 6 is a front elevation of the punch of Figure 5.

Referring particularly to the drawings, the numeral 2 designates a laboratory table 40 having supporting legs 3 and a vertical front wall 4 projecting upwardly from the top thereof. The wall 4 is provided with a suitable opening 5 through which the operator may manipulate the apparatus 6 on 45 the table 2.

As is often the case in conducting laboratory tests or experiments, gases are generated which will explode, breaking the apparatus and scattering particles in all directions. These explosions are very dangerous 50 and the operator has often been very badly injured by flying particles.

To prevent the operator being injured by the flying particles of exploded apparatus 55 I have provided a flexible metal mesh screen 7, which is secured and suspended by strips

8 along the top edge of the opening 5, so as to hang between and separate the operator from the apparatus 6.

The screen 7 is composed of transverse 60 interlinked spirally wound strands 9, which are wound sufficiently close to form a substantial barrier to prevent the passage of flying particles and yet are sufficiently open to permit substantially unobstructed vision 65 of the apparatus 6, so that while the operator is protected from flying particles of the apparatus in case of an explosion, yet he may readily perceive the actions of the test or experiment.

70 The strands 9 are composed of comparatively light flexible wire so that when the operator puts his hand under the screen to work or adjust the apparatus 6, the screen will drape or fold around his hand substantially as shown in Figure 2.

75 In Figures 5 and 6 I have shown my screen applied to a power punching machine to protect the operator thereof from flying particles of metal without interfering with 80 his view of the work. In this construction the punching machine is manipulated in the usual way. That is, the operator stands in front thereof and positions the work piece 10 on the die 11 secured in the base of the 85 machine and operates lever 12 to release the punch 13 so that it may be forced through the work piece 10. My screen 7 is provided with a suitable binding strip 8^a along its one side and is suspended from brackets 14 90 secured to the head 15 of the machine, so as to hang between the operator and the work.

95 While I have shown my screen as applied to a laboratory table and a punching machine it is in nowise limited to such use, since it may readily be adapted to many other machines and apparatus where it is desired to protect the operator from the danger of flying particles of metal, glass, 100 etc., without obscuring his view of the machine or apparatus and the work.

I claim:—

1. The combination with a laboratory table having a vertical front wall extending 105 upwardly from the top thereof, and provided with a suitable opening through which an operator may manipulate any desired apparatus supported on said table, of a safety screen adapted to close said opening to prevent objects that may be exploded on said table striking the operator, said screen com-

- prising a flexible metallic intermeshed member having its one side secured along the top of said opening, and having its other three sides free.
5. 2. The combination with a laboratory table having a vertical front wall extending upwardly from the top thereof, and provided with a suitable opening through which an operator may manipulate any desired apparatus supported on said table, of a safety screen adapted to close said opening to prevent objects that may be exploded on said table striking the operator, said screen comprising a flexible metallic intermeshed member having its one side secured along the top of said opening, thereby suspending said member between the instruments on said table and the operator, said member being of sufficiently fine mesh to prevent objects 15 passing therethrough, and yet sufficiently open to allow substantially unobstructed vision therefrom.
10. 3. The combination with a laboratory table having a vertical front wall extending upwardly from the top thereof, and provided with a suitable opening through which an operator may manipulate any desired apparatus supported on said table, of a safety
15. screen adapted to close said opening to prevent objects that may be exploded on said table striking the operator, said screen comprising a flexible metallic intermeshed member having its one side secured along the top of said opening, said mesh member being composed of transversely extending inter-linked spirally wound strands. 30
20. 4. The combination with a work support having a vertical front wall, and provided with an opening through which an operator may manipulate work on said support, of a safety screen adapted to close said opening to prevent objects that may be propelled with force from said work support striking the operator, said screen comprising a flexible metallic intermeshed member having its one side secured along the top of said opening, thereby suspending said member between the work on said work support and the operator, said member being of sufficiently fine mesh to prevent objects passing 35 40 45 therethrough, and yet sufficiently open to allow substantially unobstructed vision therethrough. 50

In testimony whereof I have hereunto signed my name.

JAMES L. BERNARD.
